RAILWAY-CROSSING.

1,122,325.

Specification of Letters Patent. Patented Dec. 29, 1914.

Application filed March 30, 1914. Serial No. 828,242.

To all whom it may concern:

Be it known that I, JOHN S. SPIREWFKI, Jr., a citizen of the United States, residing at Milwaukee, county of Milwaukee, and 5 State of Wisconsin, have invented new and useful Improvements in Railway-Crossings, of which the following is a specification.

My invention relates to improvements in railway crossings of that type in which a 10 channeled member is rotatively mounted at each meeting point of crossed rails and adjusted or oscillated to receive the wheel flanges of an approaching car or train on either track in the channel of said member. 15 The object of my invention is to provide means for automatically oscillating the channeled members of a railway crossing simultaneously and accurately adjusting them in proper position preparatory to the 20 passage of a car or train over the crossing.

In the drawings—Figure 1 is a plan view of a railway crossing embodying my invention. Fig. 2 is a sectional view drawn on line $z-z$ of Fig. 1. Fig. 3 is a detail plan 25 view of the actuating mechanism with the entire mechanism turned through an angle of 180 degrees.

Like parts are identified by the same reference letters throughout the several views. 30 In the drawings, A, A, are the track rails of one line of railway track and B, B, are the track rails of a cross line. These rails are connected with each other at the crossing points by a connecting member C to which 35 the ends of the rails may be welded or otherwise secured. The member C is provided with a socket D which receives an oscillatory member E, the latter being supported from the base of the socket by conical anti-friction 40 rollers e. The member E is provided with a channel E' in the upper surface of said member, which crosses said member at one side of the center and is adapted to be aligned with the line of travel of a wheel flange along the inner facing of the head of the rail A or of the head of the rail B, if 45 said member E is rotated one-quarter of a turn from its position as illustrated in Fig. 1, and in the direction indicated by the arrow in said figure. The upper surfaces of the members C and E are in the same horizontal plane with the upper surfaces of the rail heads, said members therefore bridging the crossing. Owing to the fact that member E is provided with the channel E' to

receive the wheel flange, it is obvious that jolting will be avoided, since the member C is provided with channels a, b, the channels a being adapted to receive the flanges of wheels traveling on the track A, while the 60 channels b receive those of wheels traveling on the track rail B.

A pair of solenoids G and H are employed to automatically adjust the crossing members E to the desired position. Each 65 solenoid G is electrically connected to receive current from the line conductor of a car approaching on the track rails A. It is not material whether such current is received directly from the rail or from the 70 main conductor, or from any other source of electrical energy controlled from the car. It is merely essential that the connections be such that when the car approaches the crossing upon track A, solenoid G will be 75 energized.

The core G' of this solenoid is connected with a rack bar g, which transmits its motion through a gear wheel or pinion I to the member E. The gear wheel or pinion I is preferably not connected with 80 the member E for the reason that it is not desirable that shocks applied to member E should be communicated to the actuating mechanism. For this reason I support the 85 member E upon the anti-friction rollers e

and provide it with a downwardly extending projection J loosely interlocked in a hub projection J' on the gear wheel I. The projection J and hub J' are so interlocked as to transmit rotative movements, while allowing independent vertical movements. For example, the projection J may be squared and entered in a squared socket in the hub J' as illustrated. The pull of the solenoid 90 core G' upon the rack bar g is limited by a 95 solenoid cap g'.

When the car strikes this cap, the channel E' in the oscillatory member E will be in position to receive the wheel flanges of a car on track A. It will be observed, however, that the rack bar g is also 100 connected with the solenoid core H' of solenoid H. The winding of this solenoid is energized from a source of electrical energy controlled by cars approaching on track rails B. Assuming the parts to be in the 105 position illustrated in Figs. 1, 2 and 3, it is obvious that when a car approaches on track B and energizes solenoid H, its core H' will be drawn inwardly to the cap h', thereby actuating the member E in the direction in- 110

dicated by the arrow thereon in Fig. 1, to thereby bring its channel E' into position to receive the flanges of a wheel traveling on track rail B.

5 It will of course be understood that when solenoid H is energized, solenoid G will be deenergized, since the cars may cross in but one direction at a time and an approaching car on the other track will stop at a 10 sufficient distance from the crossing to avoid energizing the solenoids relating to that track. It will also be observed that by using two solenoids, it is possible to utilize the deenergized solenoid as a guide, acting 15 cooperatively with the other solenoid to hold the rack bar g in engagement with the gear wheel I. It is further obvious that if any 20 of the crossing members should become wholly or partially displaced in the intervals between the crossing of cars on said tracks, said members will be replaced in proper position from any point of displacement as soon as the solenoid is energized upon the approach of a car. This is due to 25 the fact that the solenoid caps g', h' limit the possible oscillations of the crossing members and the magnetic pull upon the core of the energized solenoid will necessarily draw such core inwardly until it strikes the 30 cap. It is deemed unnecessary to illustrate diagrammatically or otherwise, any of the various means that may be devised for connecting said solenoids with a source of electrical energy subject to the control of an 35 approaching car, for any person skilled in this art will understand how to provide for such connections. It is not material whether such connection is made directly by the trolley or by an auxiliary contact device 40 carried by the car, or by mechanism which utilizes the weight, momentum, or tractive energy of the car to mechanically connect up an electrical switch. In the drawings I have illustrated the solenoid windings as 45 respectively connected with the track rails to which they cooperatively relate, whereby a current in the rail may pass through and energize the solenoid and thence to the ground, but this is merely illustrative of a 50 possible means for conveying the energizing current to the solenoids.

The several pairs of solenoids, together with the rack bars and gear wheels, may be securely housed in suitable metal casings L.

55 Instead of using a pair of solenoids for each of the crossed rails, I may utilize one pair of solenoids for a series of aligned crossings, as shown at the left hand in Fig. 1, where I have diagrammatically illustrated 60 a rack bar M projected through a solenoid cap g' and through the end of the housing L, said bar extending into the housing L of the adjacent crossed rails and arranged to

operate the gear I at that point through the medium of an intermediate gear. Where 65 this is done, bearing rollers O will be employed to hold the rack bar to the gear wheel.

I claim—

1. The combination with crossing track rails, of fixed and oscillatory crossing members, the fixed crossing member being provided with channels to receive wheel flanges of cars traveling along either track and the oscillatory crossing member being provided with a channel adapted to connect up the 75 channels in the fixed member along the line of either track, electromagnetic mechanism adapted to be controlled by a car upon one track for actuating said oscillatory mechanism in one direction, and similar mechanism adapted to be controlled by a car on the other track for actuating said member in the opposite direction, substantially as described.

2. The combination with an oscillatory 85 channeled railway crossing member, of a pair of solenoids each provided with a movable core, an actuating bar connecting said solenoid cores, and means for transmitting motion from said actuating bar to the oscillatory member, substantially as described.

3. The combination with an oscillatory channeled railway crossing member, of a gear wheel in slip joint connection therewith adapted to transmit oscillatory movements 95 thereto, a rack bar in mesh with said gear wheel, and electromagnetic means for actuating said rack bar in two directions, together with means for limiting the movement of said rack bar to a one-quarter turn 100 of the gear wheel in either direction, substantially as described.

4. The combination with a fixed railway crossing member provided with a socket and adapted to engage the rails of crossed 105 railway tracks, of an oscillatory member mounted in said socket, supporting anti-friction devices interposed between said member and the base of said socket, a gear wheel connected for motion transmission to 110 said oscillatory member, and a plurality of electromagnetic devices for actuating said gear wheel, one of said devices being adapted to be connected up electrically with a source of energy by a car approaching on 115 one track, and the other of said devices being adapted to be connected up electrically with a source of energy by a car approaching on the other track, substantially as described.

120 In testimony whereof I affix my signature in the presence of two witnesses.
